UNITED STATES PATENT OFFICE.

ANDREW L. RIKER, OF NEW YORK, N. Y.

DESIGN FOR AN ELECTRIC-MOTOR CASING.

SPECIFICATION forming part of Design No. 28,124, dated January 4, 1898.

Application filed November 24, 1897. Serial No. 659,718. Term of patent 7 years.

To all whom it may concern:

Be it known that I, ANDREW L. RIKER, of New York city, in the State of New York, have invented and produced a new and original Design for Electric-Motor Casings, of which the following is a specification, reference being had to the accompanying drawings, illustrating the same.

Figure 1 is a perspective view of a casing, showing my design; and Fig. 2 is a side elevation thereof.

The leading features of my design are the oblong body A, of approximately rectangular shape in cross-section, having the central portion A' projecting slightly beyond the main body entirely around the same, and the

lateral extension B, of the same height as the body, but of less width, being flat on the side b and curved approximately in the arc of a circle on the opposite side b'.

What I claim, and desire to secure by Letters Patent, is—

The design for an electric-motor casing substantially as described and as illustrated in the accompanying drawings.

In testimony whereof I have signed this specification in the presence of two subscribing witnesses.

ANDREW L. RIKER.
